TUNING SYSTEM

Application filed July 3, 1930. Serial No. 465,603.

My invention relates to tuning systems utilizable particularly in tuning radio receiving apparatus, and more particularly in tuning radio receiving apparatus of the super-heterodyne type.

In accordance with my invention, a circuit or system is tunable to oscillations or currents of any frequency within a range, while largely suppressing or eliminating the effect of undesired current or oscillations having a frequency differing therefrom, especially to a predetermined or fixed extent, by recourse to inductance and a single variable tuning capacity, which latter with a portion of the inductance effects a series resonant path for the current of undesired frequency, which accordingly has insubstantial effect upon or is bypassed from any circuit, vacuum tube or device whose terminals are those of the series resonance combination.

Further in accordance with my invention, the inductance of the series resonance combination is wholly or in part shunted by a capacity, which may be of fixed magnitude, for suitably modifying the effect of the inductance in the series resonance combination at different parts of a frequency range, and more particularly in the high frequency portion of a given frequency range.

Further in accordance with my invention a system or circuit of the character aforesaid may precede or follow another tunable circuit in cascade therewith. A plurality of tunable circuits or systems of the character aforesaid may be disposed in cascade, constituting the entire or any suitable portion of a cascade of tunable circuits.

Further in accordance with my invention, the circuit or circuits of the character aforesaid is or are utilized in a superheterodyne system, preferably in advance of the first detector tube, and preferably in immediate association with the input electrodes of the first detector tube, the series resonance combination being tunable to frequencies differing from the frequency of the desired current or oscillations by an amount substantially double the intermediate frequency of the superheterodyne system, for materially reducing or eliminating interference, of the

character commonly known as "image" or "double spot" interference, otherwise occurring.

Further in accordance with my invention, the circuit or circuits of the character aforesaid may be used in single dial or uni-control systems, in which variable tuning elements in different circuits or paths are operated mechanically in unison; and more particularly in uni-control superhetrodyne systems in which there is included in the uni-control a variable reactance or frequency-determining element of a generator of local oscillations whose frequency is varied as the tuning of the circuit or circuits progresses to produce a beat of the aforesaid intermediate frequency.

My invention resides in a tuning system and in features of arrangement and proportionment of the character hereinafter described and claimed.

For an understanding of my invention, and for an illustration of some of the various forms it may take, reference is to be had to the accompanying drawings, in which:

Fig. 1 is a diagrammatic view of a tuning system embodying my invention.

Fig. 2 is a graph comprising characteristic curves illustrative of my invention.

Fig. 3 is a diagrammatic view of a modified tuning system in accordance with my invention.

Fig. 4 is a diagrammatic view of cascaded tuned circuits including a tuning system or circuit in accordance with my invention.

Fig. 5 is a diagrammatic view of a superheterodyne receiving system embodying my invention.

Referring to Fig. 1, L and L1 are inductances together associated with the variable condenser C for tuning to the desired oscillations or currents of various frequencies impressed upon the circuit in any suitable way, for example through a primary P coupled to any part of the inductance of the circuit. For the oscillations or current of desired frequency, the condenser C may be considered as in parallel to a total inductance L1 plus L, in which case, as in ordinary tunable loops or circuits, as resonance a maximum

difference of potential exists across the terminals of the condenser C, and to the terminals of the condenser C are generally connected the input terminals of a vacuum tube, amplifier, detector, or of any other suitable device. In the present instance, however, the terminals employed are those indicated at 1 and 2, which in the example illustrated are connected respectively to the grid *g* and the cathode *c* of an amplifying, detecting or other suitable vacuum tube, either of the usual three electrode type, or of a multi-grid type, including those of the so-called shield or screen grid type.

The arrangement is such that in effect the maximum potential at resonance is not impressed upon the grid and cathode, but a lesser potential is impressed thereon due to the fact that the grid *g* is in effect connected to a point intermediate the terminals of the inductance comprising L and L₁ in series. Nevertheless, this lesser potential is at a maximum when the parallel resonance combination L₁, L and C is tuned to resonance for the desired current or oscillations representing the signal or message to be received.

The combination LC, however, is tunable to series resonance at a frequency higher than that of the oscillations or current representing the desired signal, and as to such other and higher frequency, the combination LC is of extremely low impedance, thereby substantially eliminating the effect of the current of other and higher frequency upon the input elements *g* and *c*. At series resonance of the combination LC, substantially the only impedance is the resistance of the winding of the inductance L, and this is so inconsequential that the aforesaid effect across the grid *g* and cathode *c* is negligible.

While ordinarily the selectivity of the parallel resonance combination L₁ plus LC is sufficient to exclude oscillations or currents of other frequencies, there are cases where, as in superheterodyne systems hereinafter described, it is desirable or necessary to take further steps to eliminate such other frequencies; and a circuit of the character of Fig. 1 is provided with very powerful or effective means for procuring such additional discrimination, which in the example described is effected by a single variable tuning condenser available for both tuning to the desired signal frequency and to effect a series resonance path for the undesired signal frequency.

For the desired signal frequency the magnitude of the inductance L and L₁ and the magnitude of the capacity C are such as to effect resonance. The connection of one of the terminals of the translating device, as the grid *g* of the vacuum tube, to a point between the inductance elements L₁ and L produces some loss in resonant voltage, for it is somewhat less than the resonant voltage

across the condenser C, but nevertheless there will be a sufficiently large difference of potential between the points 1 and 2 to procure effective transfer to the device whose terminals are connected to the points 1 and 2. 70 This loss in voltage, however, is readily made up by amplification, by one or more of the vacuum tubes of the receiving system. For any setting of the tuning condenser C for desired frequency, the series combination LC 75 exhibits practically no impedance or reactance for some other and higher frequency whose effect, therefore, upon a device connected to the points 1 and 2 is practically eliminated. A single value of the inductance L will not maintain perfect series resonance for the interfering frequency, when differing a fixed amount from the desired frequency, and when the condenser C is varied throughout its range of tuning to the desired 80 signals. Nevertheless, there is substantial improvement throughout the range of desired signal frequencies in the discrimination against the interfering signal, with perfect results, however, at only one such different 85 and higher interfering frequency.

Speaking in terms of present broadcast frequencies, which range from 550 k. c. (kilocycles) to 1500 k. c., and referring to Fig. 2, curve A is a curve or plot of magnitudes of inductance L in microhenries against frequencies in kilocycles. Curve A shows the variation of magnitude L necessary for a particular broadcast receiver which shall discriminate against a higher undesired frequency differing by, say, 260 k. c. from the desired frequency, throughout the range of frequencies in which interference is possible, particularly in a superheterodyne receiver. Curve A indicates the necessity for variation 100 of the magnitude of the inductance L, particularly for certain conditions hereinafter described, and to avoid actual variation of the magnitude of the inductance L, but to cause it satisfactorily to operate with sufficient exactitude, there is associated therewith another element, which will now be described.

In Fig. 3 the arrangement is the same as that of Fig. 1, except that in shunt to the whole or a suitable part of the component L of the entire inductance is shunted a condenser C₀ of suitable capacity, which, as diagrammatically represented, includes also the distributed capacity of the winding of the inductance L. This arrangement, I have found, produces a marked improvement in the elimination of the effect of the undesired signal frequency. The parallel combination of L and C₀ has an effective inductance, which increases with increasing frequency, which is in the desired direction, particularly for the purposes hereinafter described in connection with superheterodyne receivers. This parallel combination does not effect exact variation 115 of the effect of inductance L, as required by 120 125

curve A of Fig. 2, but affords a suitable compromise satisfactory from a practical standpoint. The parallel combination LC_0 does, however, afford exact magnitudes of the effect 5 of the inductance L for two desired frequencies in the range, and in any event very much enhances the discrimination in general throughout the frequency range of the desired signals. This is indicated by dotted 10 curve B, Fig. 2, where the approximation to the exact requirements indicated by curve A is shown to be close through the high frequency portion of the range, and is exact at any two suitable frequencies as those corresponding 15 with the points 3 and 4, and between these frequencies, corresponding to the points 3 and 4 the approximation is close enough for practical purposes, as indeed is the case even to the left of the point 3 for lower 20 frequencies, because in that portion of the entire range the selectivity of a circuit, such as indicated in Figs. 1 and 3, is greater in any event than for the higher frequencies of the range, and because for the higher frequencies 25 of the range the percentage difference between the desired signal and interfering signal is less.

For the purposes described, the parallel combination LC_0 is so adjusted or proportioned 30 as to procure suitable or proper values of the effective inductance in the higher frequency portion of the range. The maladjustment, such as indicated by the divergence of the curves A and B is extremely small in 35 the high frequency portion of the range. The curve B corresponds with an inductance L of about 110 microhenries and capacity C_0 of about 26 micro-microfarads; the inductance L_1 may be of any other suitable magnitude, as, for example, substantially equal to 40 L, but in any event the sums of the inductances L and L_1 are those essential for tuning with the variable capacity C to the desired signal frequencies.

Referring to Fig. 4, D is a receiving antenna or equivalent, between which and earth E, or other counter capacity or equipotential conductor, is connected the primary p of a radio frequency transformer, any suitable 50 amount of which may be included in the antenna path by the switch α . Coupled to the primary p is the secondary s , which with the primary P is tunable to the desired signal frequency by the variable condenser C_1 . The primary P is coupled to the inductance 55 L_1 of a circuit of the character of Fig. 3, having, as before, the inductance L shunted by the capacity C_0 , in series with the tuning condenser C. This circuit intervenes between the first-named circuit sPC_1 and a following tuned circuit comprising the inductance L_2 , shunted by the variable condenser C_2 , for tuning to the desired signal frequency. The three tuned circuits are in 60 cascade, each tunable to the desired frequency. 65

The circuit L_2, C_2 is coupled to the intermediate circuit of the character of Fig. 3 through a small coupling condenser K. Across the terminals 4 and 5 are connected the input terminals of an amplifying, detecting 70 or other vacuum tube, or the terminals of any other translating device. Fig. 4 illustrates that a circuit of the character of either Fig. 1 or Fig. 3 may comprise one of a series of cascaded tunable circuits, and that it may 75 either precede or follow a tunable circuit of the cascade.

As indicated by dotted lines in Fig. 4, the rotors of the several tuning condensers C, C_1 and C_2 may be mechanically coupled to 80 effect a uni-control or single dial operation. This system may precede any type of apparatus, particularly radio frequency amplifying apparatus; and particularly in a superheterodyne system the input grid and 85 cathode terminals of the first detector may be connected to terminals 4 and 5.

In Fig. 5 is shown a superheterodyne receiving system in which is embodied my invention, specifically of the type indicated in 90 Fig. 3, though it will be understood that there may be utilized therein a circuit in accordance with Fig. 1.

In the superheterodyne method of reception, upon the desired signal oscillations are 95 superimposed locally generated oscillations of suitable difference in frequency. There results a beat current having a frequency equal to the difference between the frequencies of locally generated and desired signal oscillations. The superimposed oscillations are impressed upon the input terminals of a detector, generally a vacuum tube detector, in whose plate circuit appear oscillations of the aforesaid beat frequency, which latter is 100 also termed the intermediate frequency, for it is still a high frequency intermediate the frequency of the desired signal oscillations and the audio frequency currents representing the desired signal, as speech, music, etc. 110 The oscillations of intermediate or beat frequency are amplified by the so-called intermediate frequency amplifier, which is usually designed to amplify only a narrow band of frequencies. When, as in broadcast reception, it is desired to receive signal oscillations of various frequencies, corresponding to different broadcasting stations, the frequency 115 of the locally produced and superimposed oscillations is adjusted, so that the difference or beat frequency is substantially constant or falls within the band to which the intermediate frequency amplifier is generally tuned. Undesired signal oscillations, 120 those of frequencies other than that of the desired signal, produce in general beat frequencies falling outside of the band to which the intermediate frequency amplifier is tuned, and the undesired signal oscillations are in effect not received, or in any event produce 125 130

negligible effect, and the system is accordingly selective.

- There is a condition, however, under which undesired signals can produce serious interference, because, it is evident, one signal frequency above and another signal frequency to an equal extent below the frequency of the locally generated oscillations will produce the same specified difference or intermediate frequency, and consequently be converted by the detector to the same intermediate frequency, and accordingly there will arise serious confusion or interference between the signals of the two frequencies, when that of only one of the frequencies is desired. Such interfering signals, producing the same intermediate frequency, are spaced apart in frequency by twice the intermediate frequency. This type of interference is frequently referred to as the "double spot" or "image" effect; and it is one of the principal objects of my present invention materially to reduce or eliminate the possibility of such interference.
- This object is attained by recourse to a circuit of the character of Fig. 1, and preferably of the character of Fig. 3, utilized in advance of the first detector of a superheterodyne system, and preferably immediately in advance thereof, as indicated in Fig. 5, where the first detector is the vacuum tube V, in this instance a screen grid detector having the control grid *g*, cathode *c* heated by the electric heater *h*, screen or shield grid *b*, and anode or plate *d*. The grid *g* and cathode *c* are connected as indicated in Fig. 3, with the intervention, between the cathode *c* and the terminal 2 of the preceding tunable circuit, of the coil or transformer winding *s*1 in series with the resistance *r*, the latter shunted by capacity *k*. To the coil *s*1 is coupled a coil *p*1 of the local oscillator O, which produces continuous oscillations of suitable amplitude, and of a frequency, determinable by the variable capacity *C*3, whose rotor, as indicated by the dashed lines, may be mechanically coupled for operation in unison with the rotors of the tuning condensers C and C1. The local oscillator O is of the vacuum tube type, having coupled plate and grid circuits producing oscillations of the frequency aforesaid, traversing the winding *p*1, and through the coil *s*1 superimposing oscillations of that frequency and of suitable amplitude upon the oscillations in the grid circuit representing the desired signal, which generally comprises continuous or sustained oscillations modulated in any way, as by sound waves for transmission of music and speech. The beat current or current of intermediate frequency, appearing in the anode circuit of the detector tube V, is maintained constant by suitable adjustment of the condenser C3 with relation to the adjustment of the condenser C, and of condenser C1 if an

additional tuned circuit is utilized. This intermediate frequency may be assumed to be 130 k. c. It is impressed upon the grid or input circuit of the first intermediate vacuum tube amplifier V1 in whose plate circuit is an inductance L3 tuned by capacity comprising a condenser K3 for a narrow band of intermediate frequencies, within which lies the aforesaid frequency of 130 k. c., for example. The amplified intermediate frequency current is then impressed upon the input circuit of a generally similar or equivalent vacuum tube amplifier V2 in whose output circuit is a similar combination of inductance L4 with tuning capacity comprising a condenser K4 for tuning to the same narrow band of intermediate frequencies. The intermediate frequency thus further amplified is impressed upon the grid circuit of the second detector comprising the vacuum tube V3, in whose anode circuit appears the audio frequency current representing the signal, as speech, music, or the like. Coupled to the plate circuit of the second detector V3 is the input circuit of an audio frequency amplifier tube V4 whose output circuit is coupled to the input circuit of the push-pull amplifier tubes V5 and V6, in whose output system is disposed the signal translating instrument or loud speaker I.

A system of the character described may utilize any type of power, such as direct or alternating current, as well understood in the art. In the example illustrated, the power supply is of the alternating current type. The power supply conductors 6 and 7 connect through any suitable means as a switch or lamp socket with a source of commercial alternating current, from which current is accordingly delivered to the primary of the transformer T, having a secondary S delivering alternating current of suitably high potential, rectified by a thermionic tube V7, for supplying through a suitable filter as indicated uni-directional or substantially direct current to the anode circuits of the several tubes V to V6 inclusive and O. One or more additional secondaries S1 of transformer T supply alternating current, as for heating the cathode heater resistances *h* of the several tubes, all as well understood in the art.

In a superheterodyne system, generally of the character above described, it has been the practice to employ cascaded circuits, in advance of the first detector tube, tuned to the desired signal frequency, to exclude the undesired signal differing from the desired signal by twice the intermediate frequency. It is evident, however, that in the case where the interfering signal is that of a nearby powerful station, while at the same time the desired signal is relatively weak, a very high degree of discrimination is required, and it is this unusual degree of discrimination which is effected in accordance with my invention.

by employing the circuit of the type of Fig. 1, or, and preferably, Fig. 3.

As above indicated in connection with Fig. 5, it has been the practice, and convenient, in uni-control or single dial operation to operate the local oscillation generator O at a frequency higher than that of the desired signal by the value of the intermediate frequency, in which case the interfering signal 10 producing the aforesaid "double spot" or "image" will be higher in frequency than the desired signal by twice the value of the intermediate frequency. For such circumstances particularly, the circuit arrangement of 15 Figs 1 and 3, and particularly the latter are unusually effective, to render negligible or in-substantial the effect of the interfering or double spot signal frequency.

In order to maintain perfect operation for 20 the purposes stated, it is necessary to increase the inductance L as the capacity of the variable condenser C is decreased. Curve A of Fig. 2 indicates the variation of the inductance L necessary for a particular broadcast receiver throughout the range of frequencies 25 in which interference of the character aforesaid is possible on the part of other simultaneously operating broadcast stations. The receiver, exemplified by Fig. 2, 30 operates with an intermediate frequency of 130 k. c., in which case a station radiating waves of a frequency of 1500 k. c. tends to cause interference with reception of a desired signal of 1240 k. c.; and a station radiating waves at a frequency of 810 k. c. causes 35 interference with a desired signal frequency of 550 k. c. Accordingly, the range throughout which interference of the type referred to is encountered lies in the receiving range 40 between 1240 k. c. and 550 k. c. It is for this latter range that the curve A shows the necessary values of inductance L to maintain the condition of series resonance of the combination LC as C is varied throughout this 45 range for tuning to a desired signal frequency.

By the parallel combination LC_0 , Figs. 3 and 5, the effect of the inductance L increases with increasing frequency or with 50 decreasing tuning settings of the condenser C; and this change is in the desired sense or direction. Exact magnitudes of effect of inductance L are procured at any two frequencies, (corresponding with points 3 and 55 4 for example) in the high frequency portion of the range within which the interference of the type described occurs, i. e., between 1240 and 550 k. c. Or the two frequencies at which the effect of inductance L 60 is exactly right may be 550 and 1240 k. c., in which case there will be deviation from correct values in the middle of the range in question. Between the points 3 and 4, as aforesaid, the exact values of effect of inductance L are closely approximated, and it

is here that it is more desirable that there be exactitude, because the selectivity is lower, and the per cent difference between desired and interfering signals is less at the high frequency range. However, to the left 70 of the point 3, and for the lower frequencies, the effect is, nevertheless, highly beneficial, though not perfectly attained. For a super-heterodyne receiver of the character described, the magnitudes of inductance L and 75 capacity C_0 above given are satisfactory, and constitute one example of many proportions of the combination suitable for various ranges and purposes. Accordingly when varying the capacity of the condenser C, if 80 there occurs at the same time a very powerful signal having a higher frequency and particularly one exceeding the desired signal frequency by twice the intermediate frequency, the latter will have negligible or substantially no effect upon the detector V, and there will, therefore, be prevented the "double spot" type of interference in the plate circuit of the detector and beyond, 85 with the result that in the loud speaker or signal translating instrument I there will be no, or substantially no, reproduction of the otherwise interfering signal.

What I claim is:

1. A method of tuning to oscillations of 95 various frequencies with additional discrimination against oscillations whose frequencies differ to a substantially fixed extent from said first-named frequencies, which comprises arranging inductive and capacitative 100 reactances effecting a loop tunable to the oscillations of desired frequency, impressing upon a translating device a difference of potential related to the potential difference existing between a terminal of said loop and 105 a point which divides one of said reactances into components one of which is in series with the other of said reactances, and varying only said other of said reactances to tune 110 said loop to desired frequency and to bring into substantial resonance with the undesired frequency said variable reactance and said component of said one of said reactances.

2. A method of tuning to oscillations of 115 various frequencies with additional discrimination against oscillations whose frequencies differ to a substantially fixed extent from said first-named frequencies, which comprises arranging inductive and capacitative reactances effecting a loop tunable to the oscillations of desired frequency, impressing upon a translating device a difference of potential related to the potential difference existing between a terminal of said loop and a point 120 which divides one of said reactances into components one of which is in series with the other of said reactances, altering the effect of said component of said one of said reactances by shunting it with reactance of the other type, and varying only said other of 125 130

said reactances to tune said loop to desired frequency and to bring into substantial resonance with the undesired frequency said variable reactance and said shunted component of said one of said reactances.

3. In superheterodyne reception, a method of tuning to oscillations of various frequencies with additional discrimination against oscillations whose frequencies so differ from said first-named frequencies that reaction with both by locally produced oscillations produces substantially the same beat frequency, which comprises arranging inductive and capacitative reactances effecting a loop tunable to the oscillations of a desired frequency, impressing upon a detector a potential difference dependent upon the potential difference existing between a terminal of said loop and a point which divides one of said reactances into components one of which is in series with the other of said reactances, superimposing upon said oscillations of desired frequency locally generated oscillations of different frequency to produce oscillations of beat frequency, and varying only said other of said reactances to tune said loop to desired frequency and to bring into substantial resonance with the undesired frequency said variable reactance and said component of said one of said reactances.

4. In superheterodyne reception, a method of tuning to oscillations of various frequencies with additional discrimination against oscillations whose frequencies so differ from said first-named frequencies that reaction with both by locally produced oscillations produces substantially the same beat frequency, which comprises arranging inductive and capacitative reactances effecting a loop tunable to the oscillations of a desired frequency, impressing upon a detector a potential difference dependent upon the potential difference existing between a terminal of said loop and a point which divides one of said reactances into components one of which is in series with the other of said reactances, superimposing upon said oscillations of desired frequency locally generated oscillations of different frequency to produce oscillations of beat frequency, altering the effect of said component of said one of said reactances by shunting it with reactance of the other type, and varying only said other of said reactances to tune said loop to desired frequency and to bring into substantial resonance with the undesired frequency said variable reactance and said shunted component.

5. A method of tuning to oscillations of various frequencies with additional discriminations against oscillations whose frequencies differ to a substantially fixed extent from said first-named frequencies, which comprises arranging inductive and capacitative reactances effecting a loop tunable to the oscillations of

desired frequency, impressing upon the input terminals of a thermionic device a difference of potential dependent upon the potential difference existing between a terminal of said loop and a point which divides said inductive reactance into components one of which is in series with said capacitative reactance, and varying only said capacitative reactance to tune said loop to desired frequency and to bring into substantial resonance with the undesired frequency said variable capacitative reactance and said component of said inductive reactance.

6. A method of tuning to oscillations of various frequencies with additional discrimination against oscillations whose frequencies differ to a substantially fixed extent from said first-named frequencies, which comprises arranging inductive and capacitative reactances effecting a loop tunable to the oscillations of desired frequency, impressing upon the input terminals of a thermionic device a difference of potential dependent upon the potential difference existing between a terminal of said loop and a point which divides said inductive reactance into components one of which is in series with said capacitative reactance, altering the effect of said component of said inductive reactance by shunting it with capacity, and varying only said variable capacitative reactance to tune said loop to desired frequency and to bring into substantial resonance with the undesired frequency said variable capacitative reactance and said shunted component of said inductive reactance.

7. In superheterodyne reception, a method of tuning to oscillations of various frequencies with additional discrimination against oscillations whose frequencies so differ from said first-named frequencies that reaction with both by locally produced oscillations produces substantially the same beat frequency, which comprises arranging inductive and capacitative reactances effecting a loop tunable to the oscillations of desired frequency, impressing upon the input terminals of a thermionic detector a potential difference dependent upon the potential difference existing between a terminal of said loop and a point which divides said inductive reactance into components one of which is in series with said capacitative reactance, superimposing upon said oscillations of desired frequency locally generated oscillations of different frequency to produce oscillations of beat frequency, and varying only said capacitative reactance to tune said loop to desired frequency and to bring into substantial resonance with the undesired frequency said variable capacitative reactance and said component of said inductive reactance.

8. In superheterodyne reception, a method of tuning to oscillations of various fre-

- quencies with additional discrimination against oscillations whose frequencies so differ from said first-named frequencies that reaction with both by locally produced oscillations produces substantially the same beat frequency, which comprises arranging inductive and capacitative reactances effecting a loop tunable to the oscillations of desired frequency, impressing upon the input terminals of a 5 thermionic detector a potential difference dependent upon the potential difference existing between a terminal of said loop and a point which divides said inductive reactance into components one of which is in series with 10 said capacitative reactance, superimposing upon said oscillations of desired frequency locally generated oscillations of different frequency to produce oscillations of beat frequency, impressing upon the input terminals of a 15 thermionic detector a potential difference dependent upon the potential difference existing between a terminal of said loop and a point which divides said inductive reactance into components one of which is in series with the other of said reactances, a source of oscillations of different frequency, means for superimposing said last-named oscillations upon said first-named oscillations to produce oscillations of beat frequency, and means for varying said other of said reactances to tune 20 said loop to desired frequency and to bring said variable reactance and said shunted component of said inductive reactance into substantial resonance with the undesired frequency said variable capacitative reactance and said shunted component of said inductive reactance. 25

9. A network for tuning to oscillations of various frequencies with additional discrimination against oscillations whose frequencies differ to a substantially fixed extent from said first-named frequencies, comprising inductive and capacitative reactances forming a loop tunable to the oscillations of desired frequency, a translating device, means for impressing thereon a difference of potential dependent upon the potential difference existing between a terminal of said loop and a point which divides one of said reactances into components one of which is in series with the other of said reactances, and means for varying said other of said reactances to tune 30 said loop to desired frequency and to bring into substantial resonance with the undesired frequency said variable reactance and said shunted component of said inductive reactance. 35

10. A network for tuning to oscillations of various frequencies with additional discrimination against oscillations whose frequencies differ to a substantially fixed extent from said first-named frequencies, comprising inductive and capacitative reactances forming a loop tunable to the oscillations of desired frequency, a translating device, means for impressing thereon a difference of potential dependent upon the potential difference existing between a terminal of said loop and a point which divides one of said reactances into components one of which is in series with the other of said reactances, and means for varying said other of said reactances to tune 40 said loop to desired frequency and to bring into substantial resonance with the undesired frequency said variable reactance and said shunted component of said inductive reactance. 45

11. A superheterodyne receiver comprising a detector, a loop comprising inductive and capacitative reactances and tunable to the oscillations of desired frequency, said detector subjected to a potential difference dependent upon the potential difference existing between a terminal of said loop and a point which divides one of said reactances into components one of which is in series with the other of said reactances, a source of oscillations of different frequency, means for superimposing said last-named oscillations upon said first-named oscillations to produce oscillations of beat frequency, and means for varying said other of said reactances to tune said loop to desired frequency and to bring said variable reactance and said component of said one of said reactances into substantial resonance with undesired oscillations of a frequency which differs from the frequency of the desired oscillations by double said beat frequency. 50

12. A superheterodyne receiver comprising a detector, a loop comprising inductive and capacitative reactances and tunable to the oscillations of desired frequency, said detector subjected to a potential difference dependent upon the potential difference existing between a terminal of said loop and a point which divides one of said reactances into components one of which is in series with the other of said reactances, a source of oscillations of different frequency, means for superimposing said last-named oscillations upon said first-named oscillations to produce oscillations of beat frequency, a reactance of the character of said other of said reactances disposed in shunt with said component of said one of said reactances, and means for varying said other of said reactances to tune said loop to desired frequency and to bring said variable reactance and said shunted component of said one of said reactances into substantial resonance with undesired oscillations of a frequency which differs from the frequency of the desired oscillations by double said beat frequency. 55

13. A network for tuning to oscillations of various frequencies with additional discrimination against oscillations whose frequencies differ to a substantially fixed extent from said first-named frequencies, comprising inductive and capacitative reactances forming a loop tunable to the oscillations of desired frequency, a translating device, means for impressing thereon a difference of potential dependent upon the potential difference existing between a terminal of said loop and a point which divides one of said reactances into components one of which is in series with the other of said reactances, a reactance of the character of said other of said reactances disposed in shunt with said component of said one of said reactances, and means for varying said other of said reactances to tune said loop to desired frequency and to bring into substantial resonance with the undesired frequency said variable reactance and said shunted component of said one of said reactances. 60

14. A network for tuning to oscillations of various frequencies with additional discrimination against oscillations whose frequencies differ to a substantially fixed extent from said first-named frequencies, comprising inductive and capacitative reactances forming a loop tunable to the oscillations of desired frequency, a thermionic device, means for impressing upon the input electrodes thereof a difference of potential dependent upon the potential difference existing between a terminal of said loop and a point which divides one of said reactances into components one of which is in series with the other of said reactances, a reactance of the character of said other of said reactances disposed in shunt with said component of said one of said reactances, and means for varying said other of said reactances to tune said loop to desired frequency and to bring into substantial resonance with the undesired frequency said variable reactance and said shunted component of said one of said reactances. 65

said inductive reactance into components one of which is in series with said capacitative reactance, and means for varying said capacitative reactance to tune said loop to desired frequency and to bring into substantial resonance with the undesired frequency said variable capacitative reactance and said component of said inductive reactance.

14. A network for tuning to oscillations of various frequencies with additional discrimination against oscillations whose frequencies differ to a substantially fixed extent from said first-named frequencies, comprising inductive and capacitative reactances forming a loop tunable to the oscillations of desired frequency, a thermionic device, means for impressing upon the input electrodes thereof a difference of potential dependent upon the potential difference existing between a terminal of said loop and a point which divides said inductive reactance into components one of which is in series with said capacitative reactance, a capacity in shunt to said component of said inductive reactance, and means for varying said capacitative reactance to tune said loop to desired frequency and to bring into substantial resonance with the undesired frequency said variable capacitative reactance and said shunted component of said inductive reactance.

15. A superheterodyne receiver comprising a thermionic detector, a loop comprising inductive and capacitative reactances and tunable to the oscillations of desired frequency, said detector subjected to a potential difference dependent upon the potential difference existing between a terminal of said loop and a point which divides said inductive reactance into components one of which is in series with said capacitative reactance, a source of oscillations of different frequency, means for superimposing said last-named oscillations upon said first-named oscillations to produce oscillations of beat frequency, and means for varying said capacitative reactance to tune said loop to desired frequency and to bring said variable capacitative reactance and said component of said inductive reactance into substantial resonance with oscillations of a frequency which differs from the frequency of the desired oscillations by double said beat frequency.

16. A superheterodyne receiver comprising a thermionic detector, a loop comprising inductive and capacitative reactances and tunable to the oscillations of desired frequency, said detector subjected to a potential difference dependent upon the potential difference existing between a terminal of said loop and a point which divides said inductive reactance into components one of which is in series with said capacitative reactance, a source of oscillations of different frequency, means for superimposing said last-named oscillations upon said first-named oscillations to produce oscillations of beat frequency, and means for varying said capacitative reactance to tune said loop to desired frequency and to bring said variable capacitative reactance and said component of said inductive reactance into substantial resonance with oscillations of a frequency which differs from the frequency of the desired oscillations by double said beat frequency.

tions upon said first-named oscillations to produce oscillations of beat frequency, a capacity in shunt to said component of said inductive reactance, and means for varying said capacitative reactance to tune said loop to desired frequency and to bring said variable capacitative reactance and said shunted component of said inductive reactance into substantial resonance with oscillations of a frequency which differs from the frequency of the desired oscillations by double said beat frequency.

17. A superheterodyne receiver comprising a thermionic detector, a thermionic amplifier system associated therewith and tuned to a band of frequencies including the intermediate frequency, a local source of oscillations of variable frequency differing from the frequencies of the desired oscillations to an extent corresponding with said intermediate frequency, and means for tuning to the desired oscillations of various frequencies with additional discrimination against undesired oscillations whose frequencies differ from said first-named frequencies by substantially double said intermediate frequency, comprising a loop including inductive and capacitative reactances and tunable to the oscillations of desired frequency, connections from the input electrodes of said detector to a terminal of said loop and to a point which divides said inductive reactance into components one of which is in series with said capacitative reactance, and means for varying said capacitative reactance to tune said loop to desired frequency and to bring said variable capacitative reactance and said component of said inductive reactance into substantial resonance with said undesired oscillations.

18. A superheterodyne receiver comprising a thermionic detector, a thermionic amplifier system associated therewith and tuned to a band of frequencies including the intermediate frequency, a local source of oscillations of variable frequency differing from the frequencies of the desired oscillations to an extent corresponding with said intermediate frequency, and means for tuning to the desired oscillations of various frequencies with additional discrimination against undesired oscillations whose frequencies differ from said first-named frequencies by substantially double said intermediate frequency, comprising a loop including inductive and capacitative reactances and tunable to the oscillations of desired frequency, connections from the input electrodes of said detector to a terminal of said loop and to a point which divides said inductive reactance into components one of which is in series with said capacitative reactance, a capacity in shunt to said component of said inductive reactance, and means for varying said capacitative reactance to tune said loop to desired

frequency and to bring said variable capacitative reactance and said shunted component of said inductive reactance into substantial resonance with said undesired oscillations.

- 6 19. A superheterodyne receiver comprising a thermionic detector, a thermionic amplifier system associated therewith and tuned to a band of frequencies including the intermediate frequency, a local source of oscillations of variable frequency differing from the frequencies of the desired oscillations to an extent corresponding with said intermediate frequency, and means for tuning to the desired oscillations of various frequencies with additional discrimination against undesired oscillations whose frequencies differ from said first-named frequencies by substantially double said intermediate frequency, comprising a loop including inductive and capacitative reactances and tunable to the oscillations of desired frequency, connections from the input electrodes of said detector to a terminal of said loop and to a point which divides said inductive reactance into components one of which is in series with said capacitative reactance, a capacity in shunt to said component of said inductive reactance and having such magnitude that in the higher frequency portion of the frequency range of the desired oscillations the effect of undesired oscillations upon said detector is a minimum, and means for varying said capacitative reactance to tune said loop to desired frequency and to bring said variable capacitative reactance and said shunted component of said inductive reactance into substantial resonance with said undesired oscillations.
20. A superheterodyne receiver comprising a thermionic detector, a thermionic amplifier system associated therewith and tuned to a band of frequencies including the intermediate frequency, a local source of oscillations of variable frequency differing from the frequencies of the desired oscillations to an extent corresponding with said intermediate frequency, and means for tuning to the desired oscillations of various frequencies with additional discrimination against received oscillations whose frequencies differ from said first-named frequencies by substantially double said intermediate frequency, comprising a loop including inductive and capacitative reactances and tunable to the oscillations of desired frequency, connections from the input electrodes of said detector to a terminal of said loop and to a point which divides said inductive reactance into components one of which is in series with said capacitative reactance, a capacity in shunt to said component of said inductive reactance and having such magnitude that at two substantially separated frequencies in the higher frequency portion of the frequency range of the desired oscillations

the effect of undesired oscillations upon said detector is a minimum, and means for varying said capacitative reactance to tune said loop to desired frequency and to bring said variable capacitative reactance and said shunted component of said inductive reactance into substantial resonance with said undesired oscillations.
